TYPEWRITING MACHINE

Harry C. Yaeger, West Hartford, Conn., assignor
to Underwood Corporation, a corporation of
Delaware

Application June 28, 1944, Serial No. 542,534

13 Claims. (Cl. 197—126)

This invention relates to typewriting machines and more particularly to the machines commonly referred to as fanfold or continuous billing machines, wherein carbon sheets are supported in interleaved relation between superposed continuous webs or plies of a fanfolded web, and are shifted therealong for registration with succeeding web-portions or forms.

Such machines embody usually a part or parts which for registering succeeding web portions or forms with the carbon sheets are temporarily displaced from an out-of-way to a forwardly extended position. Therefore, if a machine of this type is equipped with a device for moving or returning the carriage by power, the operator is exposed to a dangerous condition in that a power return may be instituted while said part or parts are extended. In any event, an operator must be on constant guard to avoid accident, which is tiresome and detrimental to efficiency.

It is a general object of the invention to provide in association with machines falling in the aforesaid category, simple and efficient safety devices to render the machine only capable of power driven carriage movement when and while said extendable, carriage supported part or parts are in normal position, that is, unextended.

Another object is to prevent movement of said part or parts to extended positions whenever the carriage is being power moved.

Other objects and features will be in part obvious and in part pointed out particularly, as the following description of a preferred embodiment of the invention proceeds.

The invention is illustrated and described in association with a fanfold billing machine of the type disclosed in the patent to Wernery and Smith No. 1,132,055, dated March 16, 1915, the machine having further been equipped with a combined power carriage return and line-spacing means disclosed in the patent to Helmond No. 2,262,676, dated November 11, 1941.

In the accompanying drawings,

Figure 1 is a fractional side elevation of an upper portion of a billing machine with parts of the invention associated therewith.

Figure 2 is a front perspective view of some parts of the carriage return control mechanism disclosed in said patent to Helmond, together with a portion of a mechanism associated therewith for incapacitating the carriage return mechanism.

Figure 3 is a rear elevation of the machine with portions thereof broken away, and illustrates mainly the combined line-spacing and car-

riage return mechanism of said patent to Helmond, in normal, ineffective condition, together with a part of a mechanism for incapacitating the return mechanism.

Figure 4 is a rear elevation showing the combined carriage return and line-spacing mechanism seen in Figure 3 more skeletonized and tripped, but ineffectively as regards to carriage returning.

10 Figure 5 is a front perspective view of a billing machine carriage and the mechanism of the invention whereby power-returns of the carriage are caused to be suppressed under the afore-stated condition.

15 Figure 6 is a skeleton side view illustrating the platen frame in a displaced position, and showing further the mechanism whereby the displacement of the platen incapacitates the power returning mechanism for the carriage.

20 Referring now more particularly to the side view of Figure 1, the billing machine shown comprises a carriage 10 upon a frame generally designated by the numeral 12. The carriage includes a rail 13 which, through the medium of anti-friction elements 14, is guided to travel upon a trackway 15. From the rail 13 there rises at each opposite end of the carriage a carriage end 16. In the space between the carriage ends there is situated a displaceable platen frame 17 consisting of two end-plates 18 spanned lengthwise of the carriage by a paper table 20, as well as also by a bridge 21, see Figure 6 for the latter. Said displaceable platen frame 17 supports a platen 22 which by means of a platen axle 23 is rotatably mounted upon the opposite end-plates 18.

25 The carriage ends 16 have bosses 24 supporting inwardly reaching studs 25 whereon the end-plates 18 and, therefore, the platen frame pivots, for upward and forward displacement from the position seen in Figure 1 to the position of Figure 6. At the rear of the platen 22, engaging normally pins 26 reaching inwardly from the opposite end-plates 18, there are two spaced latch arms 27 which normally lock the entire platen frame 17 down at the rear in firm contact with spaced collars 28 on a rock shaft 30 that extends longitudinally of the platen and whereon said latch arms are secured, the latter having each a hub 31 pinned to the shaft. Preferably the latch arms are formed with latching edges 32 designed to cam the displaceable platen frame downwardly into firm contact with said collars 28, the entire latching structure 27 and 30 being urged in anti-clockwise direction as viewed in Figures 1, 5, and

Figure 5, associated with the left latch arm. In the normal position of the platen frame, that is in the position seen in Figures 1 and 5, the platen bears upon conventional paper feeding rolls, not shown.

To the rear of the carriage 10 there is attached a shelf or extension 35 whereon there is guidedly supported on laterally spaced rails, for forward and rearward movement, a carbon carrier 36 which in correspondence with said patent 10 to Wernery and Smith may have blades 37 for supporting transfer sheets 39, the blades 37 extending from opposite lateral ends of the carrier between the superposed work-webs 38 or the plies of the fanfold web. Said shelf 35 and the 15 carrier partake in the letter-feed and return movements of the carriage, and for this purpose, each carriage end 16 has a rearwardly reaching bracket or extension 40 whereto said shelf 35 is attached through the medium of a rod 41, see 20 Figure 5. At the rear the shelf or table 35 may be supported to travel upon a rail, in the manner disclosed in the said patent to Wernery and Smith.

The work-webs or plies 38 are supplied from 25 the rear of the machine, and extend normally with the carbon sheets interleaved therebetween from the carbon carrier forwardly and downwardly around the bottom to the front side of the platen, where the plies rest normally rearwardly. At the outset of typing each bill, the leading edges of the work-webs are disposed a short distance above a level indicated by a type 40 42 where the types are adopted to print, see Figure 5. In the course of typing each bill the platen is usually line spaced several times to advance the web with the interleaved carbons. From time to time, usually in preparation for typing succeeding bills, the transfer sheets 39 are shifted relatively to the webs into registration with succeeding bill-forms to be typed. This is preferably done with the web in a straightened out position so that the webs or plies will not bind the carbons. In the embodiment of the invention shown, the above is made possible by mounting the platen supporting frame 17 displaceably for upward and forward movement to the position seen in Figure 6. In said position, as is well known, the webs or plies 38 are drawn forwardly to the extent defined by a leading-edge paper-gage 43 and the transfer sheets or carbons 39 are retracted a measured distance by retraction or shift of the carbon carrier 36 rearwardly to a predetermined position. The position of the carbons 39 with respect to the webs 38 is then such that upon restoration of the platen frame 17 to the normal position the succeeding form is in position for typing with the carbons in registration therewith. According to the embodiment of the invention shown, said gage 43 is fastened for adjustment along a gage bar 44 which normally extends from the back of said paper table 18, upwardly and rearwardly. The gage bar 44, together with the gage 43, is thus normally in and out-of-way position, but becomes extended incidental to the displacement of the platen supporting frame 17 to the position of Figure 6.

In order conveniently to unlatch the platen frame 17 and to displace it thereafter, all in a single sweeping motion, the gage bar is fastened on a rod 45 which is mounted and extends longitudinally of the platen frame for limited forward rocking movement from the position seen in Figure 5, the shaft 45 having near the left carriage

end a cam arm 46 fast thereon and adopted to act upon a pin 47 provided upon the left latch arm 27, see Figure 5. It is thus evident that when the gage bar 44 is swung slightly forward, the said cam arm 46 will force the pin 47, and consequently both latches 27 rearwardly about the axis of the shaft, and that the platen frame 17 is then free for upward displacement through continued forward motion given to the gage bar 44, it being understood that the gage bar, due to its limited capacity for movement upon the platen frame will pick up the latter.

The final displaced position of the frame 17 and the gage bar 44 is established by a device comprising a stop arm 48 which in the position of the platen frame seen in Figure 6 abuts the top side of a flange 50 and which has a throw-limiting link connection 51 with the platen frame. Said stop arm 48 is pivoted upon the latch carrying shaft 30 and the composite stopping linkage 48, 51 folds as seen in Figure 1 when the platen frame is restored to normal position.

For a purpose which will become evident later, the latches 27 are always held in released position when the platen frame does not occupy the normal position. It has been said that upon initial forward displacement of the gage bar 44, the latches 27 are swung rearwardly and that the platen frame with the pins 26 thereon is then free for upward movement. During the initial displacement of the platen frame the cam arm 46 moves clear of the pin 47, but the pins 26 glide upwardly along front faces 52 of the latch arms 27, preventing therewhile restoration of the latches. Furthermore, before the pins 26 leave said faces 52, a dog 53, pivoted as at 49 to the right carriage end, swings upwardly in front of a nose 54 constituting part of the right-hand latch arm 27. Said dog has a lateral ear by means of which it cooperates with said nose and said ear, see particularly Figure 1, normally underlies the link 51 of the platen displacement limiting device. Referring to Figure 1, it will be seen that said link 51 holds said dog normally below the nose 54 so that the latch arms are not restricted thereby against forward movement. However, as the device 51, 48 unfolds to the position of Figure 6, the link 51 rises upwardly and frees the dog 53 for movement to the illustrated position under detention of a spring 56. It is to be observed that movement of the dog 53 to effective position occurs substantially at the very outset of the displacement of the platen frame 17 and prior to the time the pins 26 leave said front faces 52. Also to be noted is that with the latches 27 in released position the front faces 52 thereof are substantially clear of the orbit of the pins 26. The dog 53 is limited in its motion by engagement of an arm integral therewith, with a front face on the flange 50. During the restoration of the platen frame 17 to normal position, the pins 26 thereon pass freely down along the front faces 52 of the said latches, and, as the platen frame nears normal position, the link 51 casts off said dog from the nose 54, the result being that the cam faces 32 of the latch arms will finally swing over the pins 26 under the tension of the spring 33.

The platen is rotatable within the displaceable frame 17 by knobs 55, one at each end of the carriage, the knobs being provided on stub shafts 55^a journaled in the opposite carriage ends 16, and said stub shafts having each a gear 62 fast thereon and laterally neighboring another gear 68, the latter being fast on the adjacent end

of the platen shaft 23 and said neighboring gears being interconnected by idler gears 69 rotatably carried on the studs 25. This construction allows displacement of the platen frame 17 independently of the knobs 55.

The carriage ends 16 have each a flange 50 to mount a cross rack 57 along which are locatable margin stops 58, 59, defining respectively the limits of the carriage advance and carriage return movement. The flange 50 on the right carriage end is the one which has been described in connection with the dog 53.

For cooperation with said margin stops 58, 59 there is supported on the main frame 12 of the machine a counterstop member 60 in the form of an upright arm whose upper end 61 projects through an opening 63a in a horizontal plate 63 supported upon a housing 64, the latter forming part of the frame work 12 of the machine. The arm 60 has a slot 67 wherethrough there extends a fixed pivot pin 65, the arm being urged under the tension of a spring 66 to occupy normally the position seen in Figure 3, wherein the upper end 61 bears against one side of the opening, namely the left side as viewed in Figure 3, that is from the rear of the machine. When the carriage approaches the line end, the advance limiting margin stop 58 engages the counterstop 61 and displaces the same either for the purpose of line end locking or for automatically initiating a power return, the machine being built in accordance with the purchaser's wishes to take care of one or the other of these functions.

As has been stated hereinbefore, the machine is equipped with the power returning and line spacing means disclosed in a patent to Helmond. This mechanism will now be described briefly, it being understood that reference can be had to said patent for clarification if desired. The machine has an electric motor 70, at the rear of the machine, and from said motor extends as seen from the rear, leftwardly a motor shaft 71 ending in a gear pinion 72, said pinion driving during use of the machine a gear 73 fast on a short spindle or shaft 74. Both said gear and pinion are contained in a casing 75 which affords also journals for the shaft 71. A flanged pulley 76 is loose on the spindle 74 and has attached thereto, for winding thereon, a carriage-return draw-band or tape 77. Said spindle 74 rotates normally without rotating the pulley 76. The gear 73 has clutch teeth and the pulley 76 has splined thereto a toothed clutch collar 78 which is movable along the spindle 74 from an open clutch position, see Figure 3, to a closed clutch position, see Figure 4. A rock shaft 80 journaled on the casing 75, has fastened thereto a yoke 81 reaching into a circumferential groove of the clutch collar 78. Said rock shaft 80 when turned clockwise of Figure 5 establishes a clutch connection between the gear 73 and the clutch collar 78, and if so turned causes the carriage return strap 77 to wind on the pulley 75. The strap 77, see Figure 3, passes over a guide pulley 82 and thence over another guide pulley 83 to a pulley 84 fastened to a line-space actuating shaft 85 journaled, as seen from the rear, upon the right carriage end. The said tape or strap 77 is attached to the pulley 84 and normally wound thereabout for about a turn, wherefore pulling of the strap will rotate said pulley 84 and its shaft to some extent, such rotation being effective to line space the stub-shaft 55a at the left side of the platen 22. A spring, not shown, is provided to return said pulley to normal position and to restore the line space 75

mechanism. The draw-band actuating pulley 76 is under constant tension of a spring, not shown, to keep the draw-band taut at all times regardless of the position of the carriage. However, this latter spring has a weaker tension than the spring which is associated with the line spacing mechanism. Whenever the clutch connection is made between the gear 73 and the clutch collar 78, there is imparted a rotative movement to the pulley 76, causing the band 77 to wind on the latter, an initial movement of the band being effective to rotate the pulley 84 to actuate the line spacing mechanism, and further movement being adapted to return the carriage. The return is thereafter terminated in response to the engagement of the return limiting stop 59 with the counterstop 61, in a manner to be described later. A spring 87 anchored to the frame work and acting on an operating arm 88 secured to the shaft 80 tends to rock the latter to close the clutch. A link 90 connects said arm 88 with an arm 91 of a lever 92 fulcrumed at 93 upon the frame work. Said lever arm 91 is normally latched in the position seen in Figures 2 and 3 by a latch hook 95 of a lever 96 which is pivoted at 97 to a side member of the frame work. With said lever arm 91 thus latched, the spring 87 is normally restrained from closing the carriage return clutch. Said latch hook 95 is releasable under control of a carriage return key 98 which surmounts the front end of a key lever 100 pivoted at 101, said key lever having an actuating connection with the latch lever 96 at 102 and being under constant tension of a spring 103 to assume the normal position seen in Figure 2, wherein the front end of the lever 100 rests against the upper end of a guide slot provided in a usual key-lever guiding comb plate 104.

For instituting a carriage return the key 98 is depressed, with the result that the latch hook 95 frees the lever arm 92 for upward movement under the urge of the spring 87 and thereby causes closure of the carriage return clutch by the yoke 81. At the end of the carriage return motion imparted to the carriage, in a manner later to be described, the lever arm 91 is restored automatically a little below the position seen in Figure 2, so that if the operator has released the return key meanwhile, the said latch hook 95 will, under detention of a spring 105, move to effective position. In the event the operator still holds the key 98 depressed when the carriage return is concluded, a secondary latch hook 106 will move over the lever arm 91 just as soon as the lever 92 is restored. Said secondary latch 106 is pivotally carried on the latch lever 96 and the spring 95 is attached to the latch 106 in a relation to press the latch 106 against the latch 95 while also tending to restore the latch lever 96. As may be noted from Figure 2, the latch shoulder of the secondary latch 106 is slightly lower than the latch shoulder of the primary latch 95, wherefor when said secondary latch is effective and thereafter the carriage return key 98 is released, the lever arm 91 will be caught by the shoulder of the primary latch 95.

As has been stated the power-driven carriage return is automatically terminated as the stop 59 engages the upper end 61 of the counterstop member 60. To this end the lever 92 includes an upright arm 107 whereon there is pivoted a link 108 that in turn is pivoted to another link 110, said links forming a toggle extending transversely of the machine. And end 111 of the link 110 extends through a perforation or opening 112 pro-

vided in the housing 64. Said link 110 has a pin 113 passing into a slot of a link 114 which has a pivotal connection with the counterstop arm 60. Normally the counterstop 61 is in the position seen in Figure 3, and is thus receptive of a movement in the direction of carriage advance, within the perforation 63a. Upon release of the clutch closing lever 92 the toggle 108, 110 folds idly upwardly from the position seen in Figure 3, to a position in which a nose 118 on the toggle 10 110 directly underlies an edge 117 of a link 110 directly underlies an edge 117 of a link 116 which is guided upon the carriage, as at 119 for diagonal movement downwardly, the counterstop 61 remaining meanwhile still in normal position under the tension of the spring 66. Closure of the clutch, as has been stated hereinbefore, results first in the actuation of the line spacing mechanism, through a limited extent of rotation imparted to the pulley 81. The pulley 81 has a pin 115 20 which gives, at the conclusion of the line spacing operation, a downward, diagonal movement to the control member 116 so that the edge 117, which it will be seen is co-extensive with the length of the carriage, will give the toggle a more 25 straightened position, this having the effect to displace the counterstop leftwardly of Figure 3 within the limits of the opening 63a, the toggle link end 111 being then moving well outside of the housing 64. The condition then prevailing is such that when the counterstop 61 is displaced by the return limiting margin stop 59, the toggle 108, 110 will be effective to transmit to the lever 92 a clutch opening movement. If the carriage is in returned position and the clutch controlling lever 92 is then released by operation of the latch 95, there will ensue only a line spacing operation. This is because the counterstop 61 in such an event is in the position of Figure 3, so that the actuation of the control bar 116 will straighten the toggle 108, 110 and will restore the lever 92 to normal, open clutch position.

According to the invention it is desired to eliminate power movements of the carriage at all times when the platen is displaced, that is when the gage bar 44 is extended. The mechanism for accomplishing this will now be described.

As best seen in Figure 5, both latch arms 27 for the displaceable platen frame 17 have integral therewith downwardly extending arms 120. These arms, by means of links 121, are operatively connected, at opposite ends of the carriage, to levers 122 of a bail structure 125 which includes a rod 123 extending parallel to the carriage and being co-extensive therewith. Said bail 125 is pivoted upon studs 124 reaching toward each other from the brackets 40 of the carriage. Movement of the latch arms 27 rearwardly at the outset of the platen displacing operation results in a pivotal displacement of the bail 125 from the position seen in Figure 1 to the position seen in Figure 6, the rod 123 being moving rearwardly during such displacement. Contiguous to the left side of the housing 64 there is pivoted on a headed stud 126, a bell crank 127 comprising a forwardly reaching arm 128 and a rearwardly reaching arm 129, the former having a vertical portion normally situated just clear of the toggle link end 111, and the latter having a vertical edge slightly behind the bail bar 123. The bell crank 127 occupies normally the position best seen in Figure 1, under the tension of a spring 132, against a pin 133 projecting laterally from the housing 64.

When the latches 27 are displaced and the bail

rod 123 is consequently moved to the rear as seen in Figure 6, the bell crank 127 as a result becomes rocked rearwardly by said rod 123, so that the vertical portion of the bell crank arm 129 blocks the toggle link 110 against outward displacement from the housing 64. Should the lever 92 then be tripped to closed clutch position, as by operation of the carriage return key 98, the toggle 108, 110 will fold upwardly as illustrated in Figure 4. Obviously outward displacement of the toggle link 110 being blocked by the bell crank arm 129, the descent of the control member 116, incidental to the line spacing operation, has then a straightening influence on the toggle to impart a clutch opening movement to the lever 92. The carriage meanwhile has remained stationary inasmuch as the control member 116 moves against very little resistance and inasmuch as the carriage is resisted more strongly against movement. It will thus be seen that although the carriage return clutch may be closed after displacement of the platen, such closure will only last until a line spacing operation has ensued.

For the fact that the platen frame latches 27, in a manner already explained, are maintained in operated position throughout the displacement of the platen, no carriage return can be instituted while the gage bar 44 is in extended position.

The bail rod 123 and the bell crank 127, constitute members which for the purposes stated are equally cooperative in all positions of the carriage.

It has hereinbefore been stated that a power return of the carriage is always preceded by an operation of the line spacing mechanism and, particularly, that as a result of the actuation of the line spacing mechanism the counterstop 61 is displaced in carriage advance direction and that the toggle link end 111 is consequently extended outside of the housing 64. This, it will be seen, blocks the bell crank 127 against operation and, consequently, in view of the described association of the bail with the bell crank 127, the latches 127 are not releasable. This means that the platen frame 17 and the paper gage 44 are locked against displacement pending the termination of each instituted carriage return.

In the illustrated embodiment of the invention, the operation of the line spacing mechanism is not suppressed by the operation of the latches, but it is to be understood that means could be provided to block the lever 92 against movement to closed clutch position, thus eliminating clutch closure and thus also line spacing. This, however, would require critical adjustment of the mechanism in that if the latch 95 were temporarily actuated it would have to be capable of reassuming its normal relation with respect to the lever 92.

Also, instead of blocking the toggle 110, a mechanism could be provided to lock the carriage return key 98 against operation. Such mechanism, however, would be more complex than the embodiment of the invention herein illustrated.

It is further to be understood that the invention is capable of embodiment in different machines and in many forms.

What is claimed is:

1. In a continuous billing machine having a frame and having a carriage movable across said frame, the combination with a device on said carriage which is normally in an out-of-way position but which is displaceable to an extended position to facilitate relocation of writing material relatively to transfer material, of normally ineffective power moving means for the carriage,

means to render said power moving means effective, and means responsive automatically to block said device against displacement to an extended position whenever said power moving means is rendered effective.

2. In a continuous billing machine having a frame and having a carriage movable across said frame, the combination with a device on said carriage which is normally in an out-of-way position but which is displaceable to an extended position to facilitate relocation of writing material relatively to transfer material, of normally ineffective power moving means for the carriage, means to render said power moving means effective, and means responsive automatically to incapacitate said power moving means whenever said device is displaced, and responsive automatically to block said device against displacement to an extended position whenever said power moving means is rendered effective.

3. In a continuous billing machine having a frame and having a carriage movable across said frame, the combination with a device on said carriage which is normally in an out-of-way position but which is displaceable to an extended position for relocation of writing material relatively to transfer material, of normally ineffective power means for moving said carriage, means normally operable to render said power means effective for carriage moving, and means responsive to extending movement of said device to render said operable means incapable of rendering said power moving means effective, and responsive to effectuation of said power moving means to block said device against displacement to extended position.

4. In a continuous billing machine having a frame and having a carriage movable across said frame, normally ineffective power means for moving said carriage, means on said frame to render said power moving means effective, means including a device on the carriage operable to facilitate relocation of writing material relatively to transfer material, and means to suppress operation of said carriage supported device while said power means is effective, said suppressing means comprising a part on said frame, and a part on said carriage operable by said device, said parts being devised one for operation by the other in any position of the carriage.

5. In a continuous billing machine having a frame and having a carriage movable across said frame, power means for moving the carriage including normally ineffective motor means on the frame, means on the frame to render said motor means, and therefore said power means effective, means including a device on the carriage operable to facilitate relocation of writing material relatively to transfer material, and means to suppress operation of said carriage supported device while said power means is effective, and to incapacitate said frame supported motor means while said device is operated, said suppressing and incapacitating means comprising a part on said frame, a part on said carriage, and means operatively connecting said parts in any position of the carriage.

6. In a continuous billing machine having a frame and having a carriage movable across said frame, power means for moving the carriage including normally ineffective motor means on the frame, means on the frame to render said motor means, and therefore said power means effective, means including a device on the carriage operable to facilitate relocation of writing material

5 relatively to transfer material, and means to suppress operation of said carriage supported device while said power means is effective, and to incapacitate said frame supported motor means while said device is operated, said suppressing and incapacitating means comprising a part on said frame, and a part on said carriage, one of said parts comprising a bar extending in parallel with the carriage and being operatively associated with the other part in any position of the carriage.

7. In a typewriting machine having a frame and having a carriage movable in letter-feed and in return direction on said frame, the combination with a device on said carriage which is displaceable to an extended position for relocation of working material relatively to transfer material, of means on the carriage operable to effect line spacing, normally ineffective power means to operate said operable means and to return said carriage successively, means to render said power means effective, and means conditioned by the power-operation of said operable means to block said device against displacement to extended position.

25 8. In a continuous billing machine having a frame and having a carriage movable in letter-feed and return direction across said frame, the combination with a device on said carriage which is normally in an out-of-way position but which is displaceable to an extended position for relocation of writing material relatively to transfer material, of a line-spacing mechanism on said carriage, normally ineffective power means adapted successively to operate said line-spacing mechanism and to return the carriage, means normally operable to render said power means effective, and means operative while said device is extended, to incapacitate said power means with regard to carriage returning, but not with regard to line spacing.

9. In a typewriting machine having a frame and having a carriage movable across said frame, a platen, means mounting said platen on said carriage for movement from a typing position to a position facilitating positioning of writing material, means normally latching said platen in said typing position, operable independently of the position of the carriage to free the platen for displacement, normally ineffective power 45 means for moving the carriage, means to cause said power means to impart movement to the carriage, means, comprising means operable independently of the position of the carriage to render said power means incapable of imparting movement to the carriage, and means to release said latching means and concomitantly to operate said operable means.

10. In a typewriting machine having a frame and having a carriage movable across said frame, a platen, means mounting said platen on said carriage for movement from a typing position to a position facilitating positioning of writing material, latching means for normally retaining said platen in said typing position, a paper gaging device displaceable on said carriage, normally ineffective power means for moving the carriage, said paper gaging device being displaceable and said latching means being releasable, independently of the position of the carriage, means to cause said power means to impart movement to the carriage, means comprising means operable independently of the position of the carriage to render said power means incapable of imparting movement to the carriage, and means controlled by an initial displacement of said gaging device

to release said latching means and substantially concomitantly to operate said operable means.

11. In a typewriting machine having a frame and having a carriage movable across said frame, a platen, means mounting said platen on said carriage for displacement from a typing position to a position facilitating positioning of writing material, means normally latching said platen in said typing position, a paper gaging device displaceable on said frame from an out-of-way to an extended position in any position of the carriage, normally ineffective power means for moving the carriage, including an electric motor on said frame and a drive from said motor to said carriage, said drive including a normally open clutch on the frame, control means for said clutch to cause a motor driven movement of the carriage, means operable in any position of the carriage to render said control means incapable of causing a motor driven movement of the carriage, and means controlled by the displacement of said gaging device, to release said latching means, to operate said operable means, and to displace said platen mounting means.

12. In a typewriting machine having a frame and having a carriage movable across said frame, a platen, a device mounted on said carriage for movement from a normal position to a position facilitating positioning of writing material, latching means normally retaining said device in normal position but being movable to a released po-

sition in any position of the carriage in order to allow displacement of the device, normally ineffective power means for moving the carriage, means to render said power moving means effective for moving the carriage, means operable by operation of said latching means independently of the position of the carriage, to render said power means incapable of imparting movement to the carriage, and means to retain said latching means in operated position upon initial displacement of said device and pending restoration thereof to typing position.

13. In a continuous billing machine having a frame and having a carriage movable across said frame, the combination with a device on said carriage which is normally in an out-of-way position but which is displaceable to an extended position to facilitate relocation of writing material relatively to transfer material, of normally ineffective power moving means for the carriage, means to cause said power moving means to impart movement to the carriage, means to block said device against displacement to an extended position whenever said power moving means is caused to impart a movement to the carriage, said blocking means, comprising, a part on the frame and a part on the carriage, one of said parts comprising a bar extending parallel to the carriage and being operatively associated with the other of said parts in any position of the carriage.

HARRY C. YAEGER.
